CLAIM

The ornamental design for a perfume bottle, as shown and described.

DESCRIPTION

FIG. 1 is a front elevational view of a perfume bottle showing my new design; the opposite side being a mirror image thereof;

FIG. 2 is a side elevational view; the opposite side being
a mirror image thereof;

FIG. 3 is a top plan view; and

FIG. 4 is a bottom plan view thereof.

FIG. 1

FIG. 2

FIG. 4
